F. C. S. KNOWLES

SIGNAL DEVICE FOR VEHICLES

Filed Nov. 22, 1921

UNITED STATES PATENT OFFICE.

FREDERICK C. S. KNOWLES, OF FREEPORT, NEW YORK.

SIGNAL DEVICE FOR VEHICLES.

Application filed November 22, 1921. Serial No. 517,139.

To all whom it may concern:

Be it known that I, FREDERICK C. S. KNOWLES, a citizen of the United States, residing at Freeport, Long Island, in the county of Nassau and State of New York, have invented certain new and useful Improvements in Signal Devices for Vehicles, of which the following is a specification.

10 This invention relates to rear signals for automobiles and the object of the invention is to provide a device which will be automatic in operation, effective as a warning signal both day and night, and compact and 15 pleasing in appearance, with incidental simplicity of construction and economy of manufacture.

Other objects and aims of the invention more or less broad than those stated above, 20 will appear in the course of the following description of the elements, combinations, arrangements of parts and applications of principles constituting the invention; and the scope of protection contemplated will 25 appear from the claims.

In the accompanying drawings, which are to be taken as a part of the specification, and in which I have shown a merely preferred form of embodiment of the invention, 30 Figure 1 is a rear elevation of a portion of an automobile, with my improved signal mounted on top of the left rear mud guard; Fig. 2 is a horizontal section on the line 2—2 of Fig. 3; Fig. 3 is a side elevation partly in section with the parts in a non-signaling position; Fig. 4 is a detail section on the line 4—4 of Fig. 3; Fig. 5 is a section on the line 5—5 of Fig. 2; Fig. 6 is a section on the line 6—6 of Fig. 3; Fig. 7 is a section on the line 7—7 of Fig. 2, and Fig. 8 is a view similar to Fig. 1, but with the signal mounted beneath the mud guard and extending up through it.

Referring to the numerals on the drawings, 1 indicates a portion of the body of an automobile, and 2 is the left rear mud guard upon which my improved signal is mounted by means of a suitable bracket 3.

Secured to the bracket 3 is a base plate 4, 50 and mounted upon the base plate 4 by suitable means such as screws 5 is a casing 6 open at the bottom and having a top 7.

Mounted within the casing 6 and so dimensioned as to fit snugly between the top 55 7 of same and the base plate 4, so that there can be no rattling, is a mutilated sheave 8

having a post 9 cast integrally therewith, and adapted to be supported in suitable bearings in the base plate 4 and top 7 of the case 6. The post 9 is provided with a longitudinal bore 10 extending through its entire length to accommodate the admission and exit therefrom of wires for electrical connections as will be more fully hereinafter pointed out.

The sheave 8 has an annular groove 11 extending over a portion of its periphery, and cast integrally therewith is a pin 12 surrounded by a suitable recess, over which is slipped a loop 13 in a cable 14. The pin 12 also serves as a connection for one end of a spring 15, the other end of which is secured to the top 7 of the casing 6 by means of a screw 16.

The parts thus described are so designed as to permit of easy assembly within the casing 6 when the latter is inverted.

A lug 17 is cast integrally with the top 7 of the casing 6 and serves as a stop when the parts are in a normal or at rest position, as shown in Fig. 6, when a shoulder 18 on the sheave 8 engages the lug 17, the spring 15 holding the shoulder 18 against the lug 17.

The base plate 4 is provided with a hole 19 the edges of which are rounded and through which the cable 14 passes, and is flexibly connected, not shown in the drawings, to the brake, pedal lever, or other suitable portion of the automobile associated with means for stopping same, whereby the movement of said brake lever will cause the cable 14 to rotate the sheave 8 which in turn will rotate the post 9, a second shoulder 20 serving to limit such rotation by engaging the lug 17 so that the sheave and post will move substantially 90 degrees.

Mounted on the top of the post 9 and secured thereto by a screw 21 is a signal arm 22 having two members 23 and 24 secured together by means of the screw 21 and another screw 25.

Between the members 23 and 24 is a water-tight washer 26 and these members are so shaped, with respect to their inner surfaces, as to provide sufficient space therebetween to mount an electric lamp bulb 27 and channels for connecting wires extending upwardly from the post 9.

The member 23 is of much greater length than that of member 24 so that a space will be provided on its exposed inner face as shown in Fig. 3 for a suitable warning, such

as the word "Stop" which may be in raised type and of a different and contrasting color from that of the general immediate background adjacent the letters. I have found 5 that white letters with a bright red background meet the desired requirements.

As a further, but subordinate signal, the member 23 is perforated as at 28 for the purpose of admitting light therethrough, so 10 that any automobile approaching from an opposite direction, more particularly at night and when the rear warning signal is in operation and the electric lamp bulb is lighted, will receive an indication that a 15 signal is being operated to warn an automobile in the rear of the signal. If desired, these openings may be covered with red glass, for more emphatic signal effect.

Electrical connections are provided so 20 that when the signal arm 22 is moved to the signaling position, as in Figs. 1 and 8, the electric light circuit will be closed and the lamp thus connected will illuminate the extending portion of the member 23 and the 25 lettering thereon, the member 24 at this time constituting a shield to provide indirect lighting and screen the direct light from the eyes of the driver of the rear automobile.

An annular flange 29, half of which is on 30 each of the members 23 and 24, provides protection from rain, snow, etc., which will thus be prevented from entering the top of the casing and short circuiting the lamp or otherwise injuring the parts assembled with 35 in the casing, the washer 26 extending to the bottom of the flange and being shaped to conform to the configuration of the respective members of the signal arm.

The electrical connections are more particularly shown in Figs. 3, 6 and 7, and may, in preferred practice, be connected to the regular tail lamp circuit, but for purposes of illustration I have shown a battery 30 connected to a day switch 31, and from thence 40 to one of the lamp terminals. The other lamp terminal is connected by a wire passing through bore 10 and extending through the side of the post, to a spring contact 32 mounted within a recess 33, in the lower face 45 of the sheave 8 and insulated therefrom by a fibre washer 34 shaped to conform to the recess 33.

When the sheave 8 is rotated from its 50 normal position the spring contact 32 will immediately engage a lug 35 extending upwardly from the base plate 4, of which it is integrally a part, and as the base plate 4 through the bracket 3 and mud guard 2 is thus grounded to the frame of the automobile a return circuit will be established to 55 the other grounded side of the battery. When the sheave is restored to its normal 60 position the circuit will likewise be broken by the disengagement of contact 32 and lug 65 35.

Thus when the signal is automatically set to warning position by the movement of the brake pedal lever, the illumination will automatically take place and at the same time, provided, of course, that the switch 31 is 70 closed, and likewise the return of the signal will be coincident with the release of the brake pedal lever, and the lamp will be extinguished.

In Fig. 8 a modified form of bracket 3' is 75 shown, adapted to be secured to the under surface of the mud guard 2.

In this form of the invention only the 80 signal arm is visible, the other parts being hidden beneath the mud guard.

Inasmuch as many changes could be made in the above construction, and many apparently widely different embodiments of my invention could be made without departing 85 from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, 95 might be said to fall therebetween.

I claim:

1. In a device of the kind described, a signal plate, said plate being recessed at one side thereof, a lamp in the recess for illuminating said plate, a guard plate mounted on said signal plate having a recess to cooperate with the recess on the signal plate for completely covering said lamp except at the side through which the light passes to illuminate 100 said signal plate, and a water tight washer interposed between the meeting edges of said guard plate and signal plate.

2. In a device of the class described, a signal plate, a container, mechanism within 110 said container for operating said signal plate to effective or ineffective position, said mechanism including a sheave having a post, said container having an opening, said post projecting through said opening, said signal plate being mounted upon said post above said opening, said signal plate carrying a guard for covering said opening.

3. In a device of the class described, a signal plate, a container, mechanism within 120 said container for operating said signal plate to effective and ineffective position, said mechanism including a sheave having a post, said container having an opening, said post projecting through said opening, said signal plate having a hub whereby it is 125 mounted upon said post, said hub being flanged adjacent said opening to form a guard therefor.

4. In a device of the kind described, a 130

signal plate, said plate being recessed, a lamp for illuminating said plate having one side thereof positioned within said recess at one end of said plate, a guard plate for the lamp secured to the signal plate, said guard plate having a complementary recess to co-operate with the recess in the signal plate

and thereby completely cover the lamp except at the side through which the light passes to illuminate said signal plate, and 10 means for operating the signal.

In testimony whereof I affix my signature.

FREDERICK C. S. KNOWLES.
